UNITED STATES PATENT OFFICE.

RICHARD F. PREUSSER, OF WASHINGTON, DISTRICT OF COLUMBIA.

LIFE-GUARD FOR STREET-CARS.

SPECIFICATION forming part of Letters Patent No. 634,834, dated October 10, 1899.

Application filed January 21, 1899. Serial No. 702,959. (No model.)

To all whom it may concern:

Be it known that I, RICHARD F. PREUSSER, a citizen of the United States, residing at Washington, in the District of Columbia, have 5 invented certain new and useful Improvements in Life-Guards for Street-Cars, of which the following is a specification, reference being had therein to the accompanying drawings.

This invention is designed to provide a life-guard for street-cars that shall be extremely 10 light and simple in construction and be capable of attachment to cars of all construction, that shall be capable of a ready attachment and detachment from the car, and be 15 capable of folding up close to the front dashboard and in that position be out of the way of the coupling devices, all as more fully hereinafter set forth.

A further essential object is to provide 20 means for resiliently supporting the scoop portion so that the impact portion thereof will have a resilient bodily movement backward and downward when it comes into contact with an object on the track-bed, whereby the 25 blow will not only be cushioned, but the danger of the object struck passing under the scoop will be avoided, the body being caught up and delivered into the receiving-net without serious injury.

30 The invention has other more minor objects in view that will appear in the course of this specification.

In the drawings, Figure 1 is a perspective view showing the life-guard in operative position and the front end of the car; Fig. 2, a perspective view of a portion of the same, showing the life-guard folded up against the dashboard; Fig. 3, a detail view showing the manner of supporting the rear ends of the 40 arms of the scoop; Fig. 4, a vertical longitudinal sectional view taken centrally through Fig. 1; Fig. 5, a detail perspective showing a slight modification.

Referring to the drawings by letter, *a* designates two vertical posts rigidly supported 45 slightly in front of the car-platform and attached thereto by suitable brackets or braces *a'*, one of these posts being at each side of the car. Each post is provided at its upper end 50 with a forward-projecting ear *b*, provided with a hole for the reception of the downward-

turned end *c* of the upper cross-bar *d* of the scoop. The lower end of each post is slotted vertically, and journaled in each of these slots is a pair of rollers *e*, the upper roller being 55 preferably set off a little to the rear of the lower roller. Working through these slots between the rollers are the rearward-extending arms *f* of the scoop, the arms bearing and working upon the rollers and being guided 60 in their back-and-forth movements by the slots. The rear ends of the arms are each provided with a downward-turned hook *g*, and their forward ends are connected by transverse rods *h* and *i*, the former being in front 65 and the latter slightly in the rear at a point below the former, said rod *i* being provided with two or more rollers *j*, which are adapted to rest upon the tracks or the road-bed when the scoop is pressed toward the ground by an 70 object on the road-bed or by the operator on the car. At a short distance from the front rods *h* and *i* the side rods are connected by another transverse rod *k*, and this rod is connected to the front rod *h* by a series of parallel flat springs *l*. Connecting rod *l* to the upper rod *d* is the receiving-net *m*, which is constructed of rope or chains or in any other suitable manner. Connected to each side edge of the net is a chain *n*, which extends 80 from the rod *d* to the rod *k* and serves to support the front portion of the scoop at the proper distance above the track. Upon each rod *f*, between rod *k* and a sliding washer *o* on the arm, is confined a coil-spring *p*, whose 85 tendency is to expand, and which therefore normally presses the washer *o* backward to the limit of its movement, which is determined by the length of chains *w*, these chains extending from rod *r* toward the rod *k*, said 90 rod *r* rigidly connecting the washers *o* and serving to brace the rear portion of arms *f* and keep them parallel.

As will be seen, the standards *a* are provided with a spring-hinge near their upper ends, enabling the upper ends of the standards to yield backward a limited distance, whereby a blow against rod *d* on the upper part of the net will be cushioned. This hinge connection consists simply of a rule-joint *r'*, having but 95 a limited backward movement, the upper part of the standard being kept normally pressed 100

forward by means of a flat spring *s*, secured to the post just below the joint.

Should it be desired to provide the motor-man with means for bringing the scoop closer to the track at will, I prefer to employ the simple device shown most clearly in Fig. 4. These devices consist, essentially, of a foot-operated bar *t*, having a suitable head on its upper end and extending down through an opening in the platform and connected at its lower end to the forward end of an angle-lever *u*, the lower end of which is connected by a loose link-joint *v'* to the rod *v*, which extends forward and is hooked over the rod *k* about midway its length. By pressing down upon the rod *t* with the foot the fender will be drawn backward and down to the road-bed against the action of springs *p*, as shown in dotted lines in Fig. 4, and when released said springs will automatically restore the fender to its normal position a little distance above the track. When the fender is removed, rod *v* is unhooked from bar *k* and is held up by means of a suitable hook *x*, depending from the car-frame, and the foot-bar *t* falls until its head rests upon the platform practically flush therewith. When the scoop is folded up against the dashboard, the rod *v* is detached from the scoop and placed in a hook *x'*, depending from bar *r*.

It will be observed that when the scoop is down in operative position the rear ends of arms *f* extend through the slotted ends of the posts, bearing upon the rollers carried thereby, the washers *o* bearing directly against the front faces of the posts, in which position it will be observed the springs serve to resiliently support the front end of the scoop. The chains are just long enough and springs *p* just strong enough to support the scoop normally at a suitable point above the road-bed, as is obvious. The rods *f* incline upward and rearward from the contact-point of the scoop and are preferably curved slightly upward from a point near rollers *e* to the hooks *g*. By reason of the upward inclination of the arms and their free support at their upper rear ends (at a point above the contact-point of the scoop) the scoop when struck by an object in front will move backward and downward to the surface of the road-bed. It will therefore be seen that by reason of this peculiar action of the scoop the blow will not only be cushioned, but the entrance of the object under the scoop will be effectually prevented. This is a valuable feature of the device, as it does away with a serious defect in the guards now in use. It will also be observed that the scoop has not only a bodily movement backward, but a sort of oscillating movement toward either side when the object strikes the scoop on either side of the center thereof, this peculiar oscillating movement being obtained by the free support of the arms in the slotted supports between the rollers and being advantageous in that it tends to throw the struck object off toward

either side of the track if the object come in contact with the scoop-frame at one side of the center thereof.

To remove the scoop, it is simply necessary to first detach rod *v* from the scoop, then lift bar *d* off the ears *e* and withdraw the rear ends of arms *f* from between the rollers, leaving nothing attached to the car but the rigid posts and parts connected to rod *v*. To fold up the scoop against the dashboard, it is simply necessary to detach rod *v* from the scoop and then lift up the front portion of the scoop, withdrawing the arms *f* from the rollers until hooks *g* engage the lower rollers, these hooks *g* and rollers serving as a sort of hinge. To lock the scoop in its folded position, a hook *s'* is attached to the upper edge of the dashboard and hooked over the rod *h*, as shown most clearly in Fig. 2. In this folded position the net will be loosely folded up in front of the platform and dashboard, and if it be in the way of the coupling devices it may be easily moved by hand to one side out of the way.

The modification shown in Fig. 5 consists in extending the ends of bar *d* outward laterally and bending them back upon themselves before entering the holes in the ears *b*, forming spring-loops *d'*, which serve to resiliently support said rod *d*. The upper ends of chains *n* are connected to loops *d'*, whereby the net is brought outward laterally far enough to shield the posts with their ears *b*, thereby preventing a person falling into the net striking against the posts or ears and seriously injuring himself. These spring-loops, as is obvious, also render the scoop-frame and net more resilient.

It will be observed that the downward and forward extending chains *n*, one being at each side of the guard-frame, do practically all the work of supporting said guard-frame, they being connected to the guard-frame at such points that the preponderance of weight in the guard-frame will be in the front of the points of connection, which manner of supporting said frame will cause the front portion thereof to normally tend downward and the rear portions of the upward-inclined side bars to normally bear upward against the upper rollers, these upper rollers thereby receiving practically all the thrust of the side bars. It will therefore be seen that whether the guard-frame be struck by an object in front or be pulled by the pull-rod it will move backward and downward to the road-bed, wedging against the same, and that the rear ends of the side bars have a free swinging movement up and down as the guard-frame moves back and forth.

Having thus fully described my invention, what I claim, and desire to secure by Letters Patent, is—

1. The combination of a car, supports carried thereby, a resiliently-supported guard-frame having rearward-extending side bars working through said supports, a roller car-

ried by each of said supports upon which said side bars work, and hooks on the ends of said side bars adapted to engage said rollers, when the guard-frame is drawn forward and form 5 a hinge-like connection with the supports.

2. The combination of a car, supports carried thereby, a guard-frame provided with side bars extending rearward and having a sliding connection with said supports, and 10 devices carried by said side bars at their rear ends and adapted to automatically engage the supports without leaving the same when the guard-frame is drawn forward and form a hinge-like connection with said supports, 15 whereby the guard-frame may be drawn forward and folded up.

3. The combination of a car, carrying pendent supports, a guard-frame having rearward-extending side bars slidingly engaging said 20 supports, the rear ends of said bars being provided with hooks adapted when the frame is drawn forward to engage the supports and act as a hinge, whereby said guard-frame may be folded up against the dashboard, substantially as set forth.

4. The combination of a car, a pair of supports extending above and below the platform, the upper ends of said supports being resiliently hinged and adapted to yield backward, a guard-frame extending forward from the lower ends of the supports, means for suspending the guard-frame from the upper hinged ends of the supports, as and for the 30 purposes set forth.

5. The combination of a car, supports carried thereby, each support carrying a roller, a guard-frame and means for freely suspending it from the car, said guard-frame having side bars extending rearward and inclining upward back of the point of suspension and bearing upward upon said rollers and having the extremities beyond said rollers free to oscillate up and down, and means for resiliently pressing the guard-frame forward.

6. The combination of a car, supports thereon, a guard-frame extending forward from said supports and detachable therefrom, a net connected to the guard-frame at its lower edge, a cross-bar connected with the upper edge of 45 the net and supported on said supports, said cross-bar having its ends formed into supporting-springs, as and for the purposes set forth.

7. The combination of a car, a guard-frame 50 projecting forward therefrom, a net connected to said guard-frame, a rod connected to the upper edge of said net, supports for this rod, these supports being set inward from the outer edges of the net and below said rod, said rod 55 being provided with means for resiliently supporting it, for the purposes set forth.

8. The combination of a car, a guard-frame 60 resiliently supported thereon and projecting forward, a net connected at its lower edge to the guard-frame, a cross-bar connected to the upper edge of the net and supporting the

frame, said cross-bar being supported on a stationary part of the car and having its ends extended laterally and formed into spring-loops lying above said stationary supporting 70 part, for the purpose set forth.

9. The combination of a car, supports projecting forward therefrom, a removable cross-bar supported on said supports, the ends of said cross-bar extending beyond said supports 75 and formed into spring-loops, a forward-projecting guard-frame, and a net extending from said guard-frame to said cross-bar, the side edges of the net being connected to said outward-projecting spring-loop, for the purposes 80 set forth.

10. The combination of a car, a guard-frame extending forward therefrom, said guard-frame having a pair of side bars having a hinge-like connection with the car, springs 85 surrounding said side bars for resiliently pressing forward said guard-frame, whereby said frame will have a resilient sliding movement back and forth and a hinge-like movement adapting it to be folded up against the 90 dashboard, a slidable washer or plate on each of said side bars to receive the thrust of the springs, a bar connecting these washers or plates, and means for limiting the movement of said washers or plates.

95 11. The combination of a car, a pair of supports depending therefrom, a guard-frame projecting forward from said supports and having rearward-extending side bars having a sliding connection thereto, said frame extending forward and downward, springs keeping said frame resiliently forward, means limiting the action of said springs, said means consisting of washers slidable on said side bars and devices, as chains, connecting said washers with a forward part of the guard-frame, suspending devices, as chains *n*, suspending the guard-frame from a point above the car-platform, and a net carried by said guard-frame, for the purposes set forth.

100 115 12. In combination with a car, supports depending therefrom, a guard or fender frame, projecting forward and downward from said support and having a forward-and-backward movement with respect thereto, said frame having rearward-extending side bars supported on said supports at a point above the front edge of the guard-frame, said side bars having a free movement back and forth and laterally in said supports, means for resiliently pressing said frame forward, means for freely suspending said frame, and a net carried by said frame, for the purpose set forth.

120 125 13. The combination with a car, supports depending therefrom, a guard-frame having side bars extending upward and rearward and having a sliding and pivotal connection with or support on said supports, the rear ends of said side bars being free to swing up and down beyond the point of connection to the 130 supports, devices, as chains, freely suspending the guard-frame, said devices extending

downward and forward, sliding washers or plates on the side bars and bearing against the supports, resilient means interposed between said washers and a part of the guard-frame whereby said guard-frame is resiliently pressed forward, substantially as set forth. In testimony whereof I hereunto affix my

signature, in the presence of two witnesses, this 21st day of January, 1899.

RICHARD F. PREUSSER.
